UNITED STATES PATENT OFFICE

GEORGE L. CHRISTMAN, OF SWISSVALE, AND JOHN B. MACNEILL, OF WILKINSBURG,
PENNSYLVANIA, ASSIGNEES TO WESTINGHOUSE ELECTRIC & MANUFACTURING
COMPANY, A CORPORATION OF PENNSYLVANIA.

CIRCUIT INTERRUPTER.

1,427,358.

Specification of Letters Patent. Patented Aug. 29, 1922.

Application filed September 18, 1918. Serial No. 254,223.

To all whom it may concern:

Be it known that we, GEORGE L. CHRISTMAN, a citizen of the United States, and a resident of Swissvale, in the county of Allegheny and State of Pennsylvania, and JOHN B. MACNEILL, a citizen of the United States, and a resident of Wilkinsburg, in the county of Allegheny and State of Pennsylvania, have invented a new and useful Improvement in Circuit Interrupters, of which the following is a specification.

Our invention relates to circuit interrupters and particularly to quick-acting field-discharge switches.

One object of our invention is to provide a field-discharge switch that shall have means for quickly snapping its contact members into and out of engagement.

Another object of our invention is to provide a double-throw switch, of the above indicated character, that shall have means for maintaining one pair of contact members in engagement until the other pair are quickly engaged and then to quickly disengage the first-mentioned pair.

A further object of our invention is to provide a quick-acting switch, of the above indicated character, that shall be simple and inexpensive to construct and effective in its operation.

In practicing our invention, we provide a rotatable member having relatively movable contact members and a lever arm mounted thereon. A lever arm is loosely mounted on the rotatable member and is normally disposed at an obtuse angle with respect to the other lever arm and a spring operatively connects the outer ends of the lever arms together. With this arrangement, the movement of the loosely-mounted lever arm will move the spring over its dead-center position and thus cause the contact members to snap quickly into and out of engagement.

In the accompanying drawings, Fig. 1 is a side elevational view of a double-throw switch embodying our invention; and Fig. 2 is a top plan view of the switch shown in Fig. 1.

The double-throw switch 1 comprises, in general, a supporting panel 2 upon which is mounted terminal members 3, 4 and 5 and supporting brackets 6 that are adapted to support the movable contact members 7 and

8 of the switch and the quick-acting operating mechanism of the same.

The terminal member 3 is operatively connected to one terminal of a blow-out coil 9 that is mounted on a supporting member 10 upon which is also mounted a stationary contact member 11 which is disposed in an arc chute 12. The terminal member 4 is operatively connected to a supporting member 13 that is provided with a stationary contact member 14 which is adapted to be engaged by the movable contact member 8. The contact members 7 and 8 are pivotally mounted on a member 15 that is secured to a shaft 16 which is journaled in the supporting brackets 6. The contact members 7 and 8 are connected, through flexible conductors 25, to the terminal member 5. A lever arm 17 is fixedly mounted on the shaft 16 and a lever arm 18 is loosely mounted thereon. A connecting means 19 is provided for receiving an operating rod (not shown) for the purpose of actuating the lever arm 18. A coil spring 20 is disposed between the ends of the arms 17 and 18, which form an obtuse angle with respect to each other when one pair of the contact members are in engagement. Springs 21 and 22 are disposed between the contact members 7 and 8 and projections 23 and 24 of the member 15, respectively, and are adapted to so restrain the relative movement of the contact members 7 and 8 that the contact member 8 engages the stationary contact member 14 before the contact member 7 becomes disengaged from the stationary contact member 11.

If it is desired to effect engagement of the contact members 8 and 14, and disengagement of the members 7 and 11, the lever arm 18 is moved to such position that the spring 20 is biased across its dead center position or, in other words, across the center line of the lever 17. When the spring 20 is moved over this position, it will cause the lever arm 17 and, consequently, the rotatable member 16 and the contact carrying member 15 to be quickly moved in a clockwise direction to first effect engagement of the contact members 8 and 14 and, after the spring 21 is expanded a predetermined amount, disengagement of the contact members 7 and 11. If it is desired to quickly effect engage-

- ment of the contact members 7 and 11, the lever arm 18 is moved in a clockwise direction and, when the spring 20 is moved over its dead-center position, it will so actuate 5 the lever arm 17 as to cause the rotatable member 16 to be quickly actuated and the contact-carrying member 15 to be snapped into such position that the contact member 7 engages the stationary contact member 11.
- 10 While our invention is particularly adapted for field-discharge switches, it is not so limited and various modifications may be made therein within the spirit and scope of the appended claims.
- 15 We claim as our invention:
1. A switch comprising stationary contact members, a movable operating member and asynchronously movable co-operating contact members for said stationary 20 contact members movably mounted on said operating member to permit the engagement of one of said movable contact members with its co-operating stationary contact member before the disengagement of 25 another of said movable contact members from its co-operating stationary contact member.
  2. A switch comprising oppositely-disposed stationary contact members, a movable operating member disposed therebetween, a co-operating contact member for each of said stationary contact members relatively movably mounted on said operating member and yieldable means for holding one 35 of said movable contact members in engagement with its co-operating stationary contact member until the other of said movable contact members has engaged its co-operating stationary contact member.
  3. A switch comprising oppositely-disposed stationary contact members, a movable operating member disposed therebetween, a co-operating contact member for each of said stationary contact members relatively movably mounted on said operating member, yieldable means for holding one 45 of said movable contact members in engagement with its co-operating stationary contact member until the other of said movable contact members has engaged its co-operating stationary contact member and means 50 for effecting the relatively-quick disengagement of one of the movable contact members from its co-operating contact member after
- the other movable contact member has engaged the other stationary contact member.
4. A switch comprising oppositely-disposed stationary contact members, a pivoted operating member disposed therebetween, a co-operating contact member for each of 60 said stationary contact members pivotally mounted on said operating member and a spring disposed between each of said pivoted contact members and said operating member for holding either one of said pivoted contact members in engagement with its co-operating stationary contact member until the other of said pivoted contact members has engaged its co-operating stationary contact member.
5. A switch comprising oppositely-disposed stationary contact members, a pivoted operating member disposed therebetween, a co-operating contact member for each of 65 said stationary contact members pivotally mounted on said operating member, a spring disposed between each of said pivoted contact members and said operating member for holding either one of said pivoted contact members in engagement with 70 its co-operating stationary contact member until the other of said pivoted contact members has engaged its co-operating stationary contact member, and an over-the-center spring device for effecting a relatively-quick disengagement of one of the pivoted contact members after the other pivoted contact member has engaged its co-operating stationary contact member.
6. A switch comprising stationary contact members, a movable operating member, co-operating contact members for said stationary contact members mounted on the operating member for movement relatively 90 to one another and to the operating member, and means for yieldingly maintaining one of the movable contact members in engagement with one of the stationary contact members until the other movable contact member has been moved into engagement 95 with the other of said stationary contact members.
- In testimony whereof, we have hereunto subscribed our names this 4th day of Sept., 1918.
- GEORGE L. CHRISTMAN.
JOHN B. MacNEILL.
